US0D1105998S

(12) **United States Design Patent** (10) **Patent No.:** **US D1,105,998 S**
(45) **Date of Patent:** **** Dec. 16, 2025**

(54) **MODEL VEHICLE GRILLE**

(71) Applicant: **TRAXXAS, L.P.**, McKinney, TX (US)

(72) Inventors: **Randy Perez**, McKinney, TX (US);
Terry Soward, Van Alstyne, TX (US);
Kent Poteet, Lucas, TX (US); **Adam Cole Ewing**, McKinney, TX (US); **Otto Karl Allmendinger**, Rowlett, TX (US);
Caleb Hix, McKinney, TX (US); **Jaime Felix Barajas**, Dallas, TX (US)

(73) Assignee: **TRAXXAS, L.P.**, McKinney, TX (US)

(**) Term: **15 Years**

(21) Appl. No.: **29/944,789**

(22) Filed: **May 30, 2024**

(51) **LOC (15) Cl.** **12-16**

(52) **U.S. Cl.**

USPC **D12/163**
